UNITED STATES PATENT OFFICE.

JOSEPH DELANEY, OF ASHLAND, PENNSYLVANIA.

IRONING-BOARD.

SPECIFICATION forming part of Letters Patent No. 317,932, dated May 12, 1885.

Application filed April 26, 1884. (No model.)

To all whom it may concern:

Be it known that I, JOSEPH DELANEY, a citizen of the United States of America, residing at Ashland, in the county of Schuylkill and State of Pennsylvania, have invented certain new and useful Improvements in Ironing-Boards; and I do hereby declare the following to be a full, clear, and exact description of the invention, such as will enable others skilled in the art to which it appertains to make and use the same, reference being to had to the accompanying drawings, and to letters or figures of reference marked thereon, which form a part of this specification.

15 My invention relates to ironing-boards; and it consists in the improvements hereinafter fully described, and pointed out in the claims.

In the accompanying drawings, forming part of this specification, Figure 1 is a perspective view, and Fig. 2 a side view, of an ironing-board embracing my invention. Fig. 3 is an end view of my improved ironing-board, looking in the direction of the arrow, Fig. 2; and Fig. 4 is an inverted plan view of a portion of the 25 ironing-board and standard.

A B are two supporting-standards provided with the base-sections C. The standard A carries at its upper extremity the metallic plate a, which is provided with a hinge, b, which 30 is secured to the lower side of the rear projecting portion of the ironing-board D.

The upper extremity of the standard B is cut away to form a tongue, d, adapted to enter a recess in the front of the ironing-board D, said recess being formed by depressed plate e, sunk into the under side of said ironing-board.

A metallic plate, f, having an upper edge of a width equal to the width of the front portion of the ironing-board, is secured on the upper front face of the standard B, so that the upper edge of said plate will support the ironing-board when it occupies the position most clearly illustrated in Figs. 1 and 2.

45 The upper edge of the plate a is of a width equal to the width of the ironing-board D, so as to afford a proper bearing for the said ironing-board at its rear.

Braces F and G connect and support the 50 standards A B at each side thereof.

A foot-lever, H, is pivoted at one end to the

base C of the standard B, and said lever has centrally attached thereto the end of a cord or cable, g, which passes through slots h therefor in the standards A B, and is finally attached on the rear under side of the ironing-board D.

By locating the lever H at the front of the structure the attendant may by depressing the same exert a traction of the cable g, pulling 6c the rear end of the board D downward and elevating the front end thereof, thus enabling a shirt or other garment to be placed thereon for the ironing process. By removing the foot from the lever H the front portion of the board D 65 will drop back in position, the tongue d of the standard B engaging the recess of the depressed plate e, and preventing lateral movement of the ironing-board D from the standard B. By providing the depressed plate e a bearing for the tongue d is secured, which will resist great strain and prevent the tongue from splitting the ironing-board.

By arranging the plate a as described the same may be readily cast so as to permit the 75 hinged connection of the plate c thereto, and at the same time afford a bearing for the rear of the ironing-board D beyond the sides of the standard A.

A sad-iron bracket, I, is pivotally attached 80 on the under side of the board D, on the rear thereof, and is adapted to be swung out from the side of the board to support a sad-iron.

By providing vertical marginal flanges i for the bracket I, and locating said bracket 85 near the rear of the board, as described, the front portion of the board may be elevated to a considerable extent without inclining the brackets I sufficiently to throw the iron therefrom.

I claim—

1. The combination, in an ironing-board, of a supporting-frame consisting in part of the standards A B, the standard A having secured at the upper rear face the plate a, extending from each side thereof and provided with a hinge, b, an ironing-board, D, connected to said standards A B, and a foot-lever pivoted to the supporting-frame and connected to the rear of the ironing-board, substantially 95 95 as described.
2. The combination, in an ironing-board, of 100

a supporting-frame consisting in part of the standards A, B, the standard A having secured at the upper rear face, the plate *a*, extending from each side thereof and provided with a hinge, *b*, a tongue, *d*, formed on the standard B, an ironing-board, D, connected to said standard A and having a depressed securing-plate, *e*, to engage said tongue, and a foot-lever pivoted to the supporting-frame and

connected to the rear of the ironing-board, to substantially as set forth.

In testimony whereof I affix my signature in presence of two witnesses.

JOSEPH DELANEY.
